UNITED STATES PATENT OFFICE.

ALFRED JOHNSON, OF PURITAN, PENNSYLVANIA.

SWITCH-THROWING DEVICE.

SPECIFICATION forming part of Letters Patent No. 712,305, dated October 28, 1902.

Application filed January 23, 1902. Serial No. 90,966. (No model.)

To all whom it may concern:

Be it known that I, ALFRED JOHNSON, a citizen of the United States of America, residing at Puritan, in the county of Cambria and State 5 of Pennsylvania, have invented certain new and useful Improvements in Switch-Throwing Devices, of which the following is a specification, reference being had therein to the accompanying drawings.

10 This invention relates to certain new and useful improvements in switch-throwing-devices, and relates more particularly to that class used for railways and the like.

The present invention has for its object the 15 provision of novel means whereby the switch-rails may be automatically thrown to any desired position and returned to their former position when the train has passed over the switch.

20 A still further object of my present invention is to provide a switch-throwing device of the above-described class that will be extremely simple in construction, strong, durable, comparatively inexpensive to manufacture, and highly efficient in its operation; furthermore, to provide novel means secured to the car that will automatically trip the switch-operating mechanism and return the same to its normal position.

25 With the above and other objects in view the invention consists in the novel combination and arrangement of parts to be herein-after more fully described, and specifically pointed out in the claim.

30 In describing the invention in detail reference is had to the accompanying drawings, forming a part of this specification, and wherein like numerals of reference indicate like parts throughout the several views, in 35 which—

40 Figure 1 is a top plan view of the main track and siding, showing the switch with my improved mechanism secured thereto. Fig. 45 2 is a perspective view of the switch-stand, showing a portion of my mechanism secured in position. Fig. 3 is a rear fragmentary 50 perspective view of a car carrying my improved tripping means. Fig. 4 is a similar view showing the tripping means placed in proper position for operating the switch mechanism. Fig. 5 is an enlarged perspective

view of the trip-lever, the latter detached from the car.

In the drawings the reference-numeral 1 represents the main track and 2 the siding: 55

3 represents the removable rails, which are secured together by the cross-bar 4. The outer end of the cross-bar 4 is pivotally connected to the outer end of the inner arm of the bell-crank lever 5, which is fulcrumed at 60 6 to the base-block 7, secured upon the tie 8. The rigid arm 9 of the bell-crank lever is pivoted at 10 to operating-rods 11 and 12, the other end of the operating-rod 11 being pivotally connected at 14 to an arm 15, secured 65 to the shaft 16, this shaft being rotatably mounted in the boss 17 of a base-plate 18, carrying the switch-stand 19, through which the upper end of the shaft 16 extends, the latter carrying at its upper end a V-shaped 70 lever-arm 20, the end of the shaft 13 being pivotally secured at 21 to an arm 22 of the shaft 23, which is likewise mounted upon the base-plate 24 and secured in the switch-stand 25. The trip-arm is slightly wedge-shaped 75 and is adapted to engage one of the arms of the V-shaped lever-arms 20 and 26 as the car passes the arms, thereby imparting movement to the shaft, which transmits movement to the movable switch-rails, as will be readily 80 seen from the foregoing description, taken in connection with the accompanying drawings.

To the rear of the car is attached a chain 85 28 by any suitable means, said chain passing around to the side of the car, where the tripping-lever 29 is hinged, as indicated at 30, said tripping-lever carrying the side flanges 31, which are adapted to contact with the V-shaped lever-arms 20 for operating the switch.

It will be noted that various changes may 90 be made in the details of construction without departing from the general spirit of my invention.

Having fully described my invention, what I claim as new, and desire to secure by Letters 95 Patent, is—

In a switch-operating device, the combination with the main track and movable rails, of a bar connected to each of the movable rails, a bell-crank lever comprising two arms 100 integral with each other and disposed at right angles and pivoted at the junction of said

arms to one side of the track, one of said arms being pivoted at its end to one end of said bar and extending at a substantial right angle thereto, operating-rods extending in opposite directions but in substantial alinement with each other having their adjacent ends pivoted to the other arm of the bell-crank at a point common to each, switch-stands located at the other ends of the operating-rods, 10 vertical shafts journaled in the switch-stands, arms rigidly connected to the shafts and piv-

oted to the other ends of the said operating-rods, said last-named arms extending at a substantial right angle to said operating-rods, and a V-shaped lever-arm mounted on 15 the upper end of each of said shafts.

In testimony whereof I affix my signature in the presence of two witnesses.

ALFRED JOHNSON.
